APPARATUS FOR DUMPING ASH IN CHAIN GRATES

Filed June 1, 1922

FIG. 1.

FIG. 2.

FIG. 4.

FIG. 3.

INVENTOR -
CHARLES WESLEY BURROUGHS.

BY *Charles W. Burroughs*

ATTORNEY.

UNITED STATES PATENT OFFICE.

CHARLES WESLEY BURROUGHS, OF MONTREAL WEST, QUEBEC, CANADA.

APPARATUS FOR DUMPING ASH IN CHAIN GRATES.

Application filed June 1, 1922. Serial No. 565,201.

To all whom it may concern:

Be it known that I, CHARLES WESLEY BURROUGHS, a subject of the King of Great Britain and Ireland, residing at Montreal 5 West, Province of Quebec, Dominion of Canada, have invented new and useful Improvements in Apparatus for Dumping Ash in Chain Grates, of which the following is a specification.

This invention relates to chain grate stokers and more particularly to the ash dumping mechanism employed in connection with chain grates.

It has for its object to provide means for automatically and continuously dumping the ashes, without affecting the heating power of the fire on the grate, and thereby maintaining a constant rate of steam production in the boiler.

A further object is to provide an ash dumping mechanism that will prevent the formation of clinkers.

A further object is to provide an ash dumping mechanism which will automatically adjust the rate of dumping to the rate of combustion of fuel on the grate.

A further object is to provide an ash dumping mechanism that is readily adaptable to any form of chain grate.

A further object is to provide an ash dumping mechanism that reduces air leakage to a minimum.

A further object is to provide an ash dumping mechanism that is located beyond the area of radiant heat from the grate fire.

A further object is to provide an ash dumping mechanism that can have parts replaced with facility and during the operation of the stoker.

The invention consists briefly in providing a series of narrow dumping plates pivotally supported on a bearing parallel and adjacent to the lower surface of the rear end of the chain grate. These bars or plates have legs, forming counterweights whereby they maintain a pressure against the chain grate in an upward direction, as will be fully set forth hereinafter.

Reference is made to the annexed drawings in which:—

Figure 1 is a vertical cross section of the mechanism.

Figure 2 is a front elevation of a portion of the mechanism.

Figure 3 is a perspective view of the set-

ting with some of the dump plates removed, and without showing the chain grate.

Figure 4 is a view showing a dump plate tilted.

In Figure 1 the chain grate 1, which may be of any type, has a bridge wall 2, built a short distance from its rear end 11, supported on a plate 21, beneath which is a tube 4, mounted on bearings 22, in the side walls, or on the stoker frame, one end extending beyond the wall, to which a hand lever 42, is attached.

Pivotedly supported on the tube 4, are a series of narrow dump plates 3, with fingers 31, of a T shaped cross-section, as shown in Figure 4, counterweight legs 32, and teeth 33, which form the bearing surfaces 34, to fit loosely on the tube 4.

The tube 4, is provided with a rib 41, along its lower side and the lever 42, has an adjustable counterweight 43.

With a construction such as above set forth, the operation of the apparatus is as follows:—

Owing to the weight of the legs 32, the fingers 31, of the dump plates 3, press upwards against the lower part of the end 11, of the chain grate 1, and collectively form an ash supporting surface. The ash which falls over the end 11, of the chain grate 1, is caught on this surface, but as the grate progresses in its rotation, it depresses some or all of the fingers 31. This movement of the fingers 31, permits a certain quantity of the ash to pass down to the ash pit below.

This movement is automatic and continuously intermittent, but as the depression of the fingers is slight, there is very little opportunity for air to leak in, whereby a cooling effect would be produced.

By means of the hand lever 42, the tube 4 and its rib 41 may be rotated and all the fingers may be operated together to dump all the ashes when cleaning the furnace as shown in Figure 4. Should any one finger get caught out of position, the hand lever 42, will readily return it to its proper position by means of the rib 41. Furthermore by adjusting the position of the counterweight 43, on the lever 42, the upward pressure of the fingers 31, on the grate bars may be increased or reduced. The grate bars will then depress the fingers they contact with against this pressure.

The position of the dump plates is such, that they are never exposed to the radiant

heat of the furnace, being protected by the bridge wall 2, the ash resting on them, and the end of the grate 11.

I have found that ordinary grey iron castings will answer for the dump plates employed in this setting, in place of the usual expensive steel fittings required in other dumping mechanism, thereby greatly reducing the cost of a complete outfit.

10 Individual dump plates can be readily removed, by tilting them, as shown in Figure 4, and then sliding them forward, and new plates can be inserted with ease and rapidity. This removal and replacement 15 may be carried on during the operation of the furnace, with slight effect on the steadiness of its steam production.

The ash which reaches the dump plates, being continuously removed therefrom, and 20 not being exposed to the high temperatures of the furnace, is not subject to clinkering.

The rate of dumping being controlled by the rate at which the grate rotates, there will always be suitable dumping for the various 25 speeds of firing.

Owing to the simplicity of its construction, and the ease of its adjustment, this invention can readily be adapted to any type 30 of chain grate stoker, and installed therein at moderate expense.

What I claim is:—

1. In a device of the class specified, the 35 combination of a chain grate with a plurality of narrow dump plates pivotally supported on a bearing parallel with the end of the grate, having their front ends bearing upwardly on the lower part of the end of the grate.

2. In a device of the class specified, the

combination of a chain grate, with a plurality of narrow dump plates pivotally supported independently on a bearing parallel to the end of the grate, having counter-weight legs adapted to cause their front ends to bear upwardly on the lower part of the 45 end of the grate.

3. In a device of the class specified, the combination of a chain grate, with a bridge wall adjacent to the end of the grate, and a plurality of independent narrow dump 50 plates, pivotally supported beneath the bridge wall, and adapted to rock against the lower part of the end of the grate.

4. In a device of the class specified, the combination of a chain grate, with a bridge 55 wall projecting towards the end of the grate, and a plurality of narrow dump plates pivotally supported beneath the bridge wall and in close proximity thereto, extending to and bearing upwardly on the lower part of the 60 end of the grate.

5. In a chain grate ash dumping mechanism, the combination of a plurality of independent L shaped narrow dump plates having 65 central bearing surfaces, formed by curved teeth, with a bearing tube journaled at each side, a rib thereon, and means to oscillate the said bearing tube.

6. In a chain grate ash dumping mechanism, the combination of a plurality of independent L shaped narrow dump plates having 70 central bearing surfaces formed by curved teeth, with a bearing tube journaled in the side walls, a rib thereon, an extension beyond one of the walls, a hand lever secured thereto, and an adjustable counter-weight on the said hand lever.

CHARLES WESLEY BURROUGHS.
